David F. Hilton

UNITED STATES PATENT OFFICE.

DAVID F. HILTON, OF DENNISON, OHIO.

CLEVIS JACK.

1,410,569.

Specification of Letters Patent. Patented Mar. 28, 1922.

Application filed December 10, 1920. Serial No. 430,388.

To all whom it may concern:

Be it known that I, DAVID F. HILTON, a citizen of the United States, residing at Dennison, in the county of Tuscarawas and 5 State of Ohio, have invented certain new and useful Improvements in Clevis Jacks, of which the following is a specification.

This invention relates to improvements in lifting jacks and has as its object to provide a jack of substantial construction capable of being readily manipulated to elevate the load and not liable to disarrangement of its parts, and in which the lifting bar will be securely supported in its elevated position so as to insure against accidental dropping of the load.

Another object of the invention is to provide a novel construction of auxiliary support in connection with the lifting bar 20 adapting the jack to be disposed beneath relatively low objects to be elevated.

In the accompanying drawings:

Figure 1 is a side elevation of a jack constructed in accordance with the present invention;

Figure 2 is a front elevation of the jack; Figure 3 is a horizontal sectional view through the jack taken substantially on the line 3—3 of Figure 1.

30 The jack embodying the invention comprises a supporting standard which is indicated in general by the numeral 1 and which comprises spaced side members 2 which stand vertically in parallel relation 35 from a base indicated by the numeral 3. The side members 2 of the supporting standard accommodate between them a vertically 40 slidable lifting bar indicated in general by the numeral 4 and this lifting bar is provided at its forward side with a longitudinally 45 extending forwardly projecting flange 5 having its forward edge formed with a series of rack teeth 6 which have their abrupt shoulders presented downwardly.

45 The flange 5 is of less thickness than the body of the lifting bar 4 so that longitudinal shoulders 7 are provided at the opposite sides of the said flange, and these shoulders are engaged and guided by flanges 8 which 50 project laterally inwardly from the relatively adjacent faces of the side members 2 at the forward edges thereof. In this manner the lifting bar is guided in its raising and lowering movement and held against 55 displacement from its position between the said side members 2. In order to further

guide the lifting bar 4 and to prevent rearward displacement thereof, the said bar is formed with a longitudinally extending slot indicated by the numeral 9, and an antifriction roller 10 is rotatably mounted upon a spindle 11 which extends transversely between the side members 2 thus positioning the roller within the slot 9 so that it will be engaged by the front and rear walls 60 of the slot for the purpose stated.

In order that the lifting bar 4 may be moved upwardly so as to elevate the load imposed upon it, an operating lever 12 is pivotally mounted as at 13 between ears 14 70 provided at the upper end of the rear side of the standard 1, and a pawl, indicated in general by the numeral 15, is operatively connected with the forward end of this lever and coacts with the rack teeth 6 of the lifting bar. The said pawl 15 is in the nature of a yoke comprising side members 17 and a cross piece 18, and the yoke is disposed to straddle the standard 1 and is pivotally connected at the upper ends of its sides 17, to 80 the forward end of the lever 12 as indicated by the numeral 19, the cross piece 18 of the yoke resting in engagement with the teeth 6 of the said lifting bar. It will now be evident that by depressing the rear end of 85 the lever 12 and consequently elevating the forward end thereof, the pawl yoke 15 will be moved upwardly and as its portion 18 is engaged with one or another of the teeth 6 of the lifting bar, the said bar will be 90 correspondingly elevated. Of course when the lifting bar is to be restored to its lowered position it is essential that the pawl yoke 15 be rendered inactive, and for this purpose a lever 20 is pivotally mounted as 95 at 21 upon one side of the standard 1 and is provided at its rear end with a handle portion 22 whereby it may be conveniently rocked upon its pivot, the forward end portion of the lever being flattened to provide 100 a finger 23 riding against the lower edge of one of the side members 17 of the pawl yoke. It will now be evident that by depressing the rear end of the lever 20 the forward end thereof will be elevated to cause the 105 finger 23 to ride upwardly against the pawl yoke and thus swing the yoke out of operative relation to the rack teeth 6 of the lifting bar 4.

In order that the lifting bar may be held 110 in elevated position as it is moved upwardly step by step through oscillation of the lever

12 the said bar is provided upon its rear side with a series of rack teeth 24, and a pawl 25 is provided as at 26 between the side members 2 of the standard 1 and is provided 15 forwardly of its pivot with an upstanding tooth 27 for coaction with the rack teeth 24. Rearwardly of its pivot the pawl 25 is provided with a lever arm 28 whereby it may be manipulated, and a spring 29 is arranged 20 to bear at its upper end against the underside of the arm 28 and at its lower end against a boss 30 formed upon the rear side of the standard 1, the spring normally holding the tooth 27 of the pawl in engagement 25 with one or another of the teeth 24 of the lifting bar. Of course when it is desired to disengage the pawl from the lifting bar to permit of lowering of the latter, this may be done by depressing the lever arm 28 of 30 the said pawl against the tension of the spring 29.

The lifting bar is provided at its upper end with a head 31 for disposal beneath the object to be elevated, and in addition to this 25 head the lifting bar is provided with an auxiliary supporting means indicated in general by the numeral 32. The auxiliary supporting means comprises an arm 33 provided at its rear end with an ear 34 as at 35 at the 30 upper end of the forward side of the lifting bar 4. A brace 36 is pivotally connected at its upper end as at 37 to the underside of the arm 33 and extends downwardly and is guided between spaced fingers 38 formed 35 upon the forward side of the flange 5 of the lifting bar. The lower end of the brace 36 is notched or shouldered as indicated by the numeral 39 and is adapted to be stepped into a stirrup 40 pivotally suspended as at 40 upon the flange 5. The stirrup 40 straddles the flange of the lifting bar 4 immediately below the spaced fingers 38 and when in the lowered position illustrated in Figures 1 and 2 of the drawings will serve as a firm seat 45 for the lower end of the brace 36 so that in this position of the parts the arm 33 is rigidly and firmly supported in a horizontal outstanding position and as its upper side is located somewhat below the plane of the 50 upper side of the head 31, it may be engaged beneath an object to be elevated and which would be located too low for the engagement of the head 31 therebeneath. Of course when it is not desired to use the arm 33, 55 the stirrup 40 may be swung upwardly and forwardly so as to permit the lower portion of the brace 36 to slide past it in a downward direction and thus permit the arm 33 to be dropped to position depending from the 60 pivot 35.

From the foregoing description of the invention the operation of the jack will be readily understood, and it will be evident that the same is of substantial construction 65 and devoid of complicated parts and that

either of its rest portions, namely the head 31 or arm 33 may be engaged beneath the object to be lifted.

Having thus described the invention what is claimed as new is:

1. A lifting jack comprising a standard including spaced upright members provided with inwardly projecting flanges, a lifting bar slidably disposed between said members and having longitudinal shoulders engaging 75 and guided by the flanges, the said bar having a longitudinal slot, a roller mounted between the side members of the standard and engaged by a wall of the said slot, and means for elevating the lifting bar. 80

2. A lifting jack comprising a standard including spaced upright members provided at their forward sides with inwardly projecting flanges, a lifting bar slidably disposed between said members and engaging 85 at its forward edge against the said flanges and guided thereby, the said lifting bar having a rack flange projecting between the first mentioned flanges, means maintaining the lifting bar engaged with the said flanges 90 upon the standard members, an operating lever mounted upon the standard, and a pawl operatively connected with the said lever and coacting with the rack flange of the lifting bar. 95

3. A lifting jack comprising a standard, a lifting bar slidably mounted thereon and having a rack at its forward edge and a rack at its rear edge, an operating lever mounted upon the standard, a pawl operatively connected therewith and coacting with the first mentioned rack, and a pawl upon the standard coacting with the second mentioned rack. 100

4. A lifting jack comprising a standard, 105 a lifting bar slidably mounted thereon and having a rack at its forward edge and a rack at its rear edge, an operating lever mounted upon the standard, a pawl operatively connected therewith and coacting with the first 110 mentioned rack, and a pawl upon the standard coacting with the second mentioned rack, the first mentioned pawl comprising a yoke pivotally suspended from the lever and straddling the standard and first mentioned 115 rack and having a cross piece coacting with the teeth of said first mentioned rack.

5. A lifting jack comprising a standard including spaced upright members, a lifting bar slidably disposed between the members 120 and provided at its forward side with a rack projecting beyond the members and at its rear side with a rack located between the members, an operating lever pivotally mounted between the members of the standard, a pawl comprising a yoke including spaced sides pivotally suspended at their upper ends from said lever and straddling the standard and further including a cross piece extending between the sides and coact- 125 130

ing with the first mentioned rack, and a pawl mounted between said members and coacting with the second mentioned rack.

6. In a lifting jack, a lifting bar having 5 a head, and an auxiliary supporting means comprising an arm pivotally mounted upon the bar and movable to a supporting position at an elevation lower than that of the head, a brace pivoted to the said supporting 10 arm, and means upon the said bar engageable by the lower end of the brace for supporting the same.

7. In a lifting jack, a lifting bar having a head, and an auxiliary supporting means 15 comprising an arm pivotally mounted upon the bar and movable to a supporting position at an elevation lower than that of the head, a brace pivoted to the said supporting arm, and means upon the said bar engageable by 20 the lower end of the brace for supporting the same, the said means comprising a stirrup pivotally connected with the bar and arranged in lowered position to be engaged by the lower end of the brace and in up- 25 wardly swung position to permit the brace to slide downwardly therethrough.

8. In a lifting jack, a lifting bar having a head, and an auxiliary supporting means

comprising an arm pivotally mounted upon the bar and movable to a supporting position at an elevation lower than that of the head, a brace pivoted to the said supporting arm, means upon the said bar engageable by the lower end of the brace for supporting the same, the said means comprising a stirrup pivotally connected with the bar and arranged in lowered position to be engaged by the lower end of the brace and in upwardly swung position to permit the brace to slide downwardly therethrough, and spaced 40 means upon the bar engaging and guiding the said brace.

9. In a lifting jack, a standard, a lifting bar slidably mounted thereon and having a rack at its forward side, an operating lever 45 mounted upon the standard in rear of the said bar, a pawl yoke pivotally suspended from the operating lever and straddling the standard and coacting with the rack, and a lever mounted upon the standard and having 50 a portion for coaction with the said pawl yoke to swing the same to inactive position when the last mentioned lever is swung in one direction.

In testimony whereof I affix my signature. 55
DAVID F. HILTON. [L. s.]
